WALTER S. PURDY, OF HUNTINGTON, WEST VIRGINIA, ASSIGNOR TO FREDERICK H. GIBBS, TRUSTEE, OF NEW YORK, N. Y.

MINE CAR.

Application filed August 27, 1924. Serial No. 734,432.

The invention relates to new and useful improvements in mine cars adapted for use in what are commonly known as low vein mines,—that is, mines in which the seam 5 is relatively thin and a few inches in thickness from top to bottom,—though it is adaptable for use in other places by mere change in dimensions.

As shown in the drawings, the car is designed primarily for use in a cradle dump, though with slight modification within the disclosure of the prior art an end gate may be substituted for either of the end walls shown and the car used in a tipple or end 15 dumping device.

Fig. 1 is a side elevational view of a mine car embodying the present invention;

Fig. 2 is an inverted plan view of the major portion of said car; and

Fig. 3 is a transverse vertical sectional view taken on line 3—3 of Fig. 2.

Referring to the parts, it will be observed that the car floor comprises planks 5^a, 6^a and 7^a intermediate the angle sills 13 and 25 14, which planks and sills rest upon the bolsters 18^a which in turn rest upon and are secured to conventional journal or axle boxes 50 (see Fig. 2) through which the axles 21 extend; said axles terminating in 30 the wheels 20, as is usual in this type of construction. As shown, the bolsters 18^a are of channel section, and thus serve as axle 35 housings. The planks 5^a, 6^a, 7^a are secured to the bolsters 18^a by bolts 51 which pass through the horizontal web portions 52 of said bolsters. Besides the planks 5^a, 6^a and 40 7^a in the center, the floor also includes planks 5^b, 7^b, and metal plates 18^b, outside the sills 13, 14. At their outer sides or edges, 45 these outer floor portions may be reinforced with side sill angles 36.

Manifestly, the wheels 20, which are intended to run on the conventional tracks, support the axles 21, which in turn support 45 the journal boxes 50; and the journal boxes underlie and support the longitudinal sills or angles 13 and 14. These sills 13 and 14 not only perform the usual function of sills, contributing to the support of the floor between and beyond the axles 21, 21, etc., but 50 they also extend beyond the ends of the car body and serve as stiffening members for bumpers or buffers 10, 11 formed by extended end portions of the floor, which portions are

enclosed between the projecting ends of said members 13, 14. The bumpers 10, 11 are shown as of conventional type, comprising the ends of the floor boards 5^a, 6^a, 7^a beyond the car body, the filler members A, and the sheet metal sheathing 12, which laps said parts and is secured to them by through bolts or other connections (not shown). The fillers A are backed up and stiffened by abutments formed by transversely extending angles B, secured to the under side 65 of the car floor and also riveted to the angle sills 13, 14. Accordingly, the sills 13, 14 assist the buffers 11, 12 in taking end shocks when cars are coupled together.

As shown in Fig. 3, the angles 13, 14 lie 70 in the longitudinally extending floor planking with their vertical flanges 13^a and 14^a interposed between adjacent planks and the flanges 15^a and 16^a being gained into the bottom portions of some of the planks. It 75 will be observed that between the wheels 20 of Figure 3 there are three planks 5^a, 6^a and 7^a shown, with portions of other planks 5^b and 7^b, and that the stiffening angles 13 and 14 are interposed between the planks 80 5^a and 5^b and the planks 7^a and 7^b.

It will be observed that if extended in a single plane, the side portions of the floor including the planks 5^b and 7^b would intersect the upper portion of the car wheels, but that 85 the plates 18^b are pressed upwardly to clear said wheels. It will be seen, therefore, that the car floor consists essentially of a main central portion or section, reinforced and stiffened by the sill angles 13, 14, and equipped 90 with the central buffers 10, 11 at its ends, and also side sections extending outward from said central section, with which side sections are combined the wheel hood sections 18^b. The normal plane of the side 95 floor sections extends outwardly and intersects the plane of the car wheels. The plates or side floor sections which lap the central floor section are rigidly connected thereto in any suitable manner, as by bolts 25. 100

Cross-braces or tie-straps such as 21^a, 21^b, 22^a, 23^b, and 24^b are provided for the floor planking, and extend beneath the side sections as well as the center sections. A bar 26 bolted to the straps and to the floor planking extends centrally of the car, substantially to the outer sides of the bumpers 10, 11; 105 as shown, it is gained into the upper surface

of the planking. Near each end of this bar 26, a coupler bar 27 is riveted thereto.

As the car shown in Figures 1, 2, and 3 is intended to be used with a rotary dumping device, it is equipped with flanged depending members 30 at each side and near each end of the body, which are intended to interlock with corresponding elements in the dumping cradle, not shown. As the lading 10 is not obliged to slide longitudinally of the floor in dumping, it is permissible to place reinforcements for the car body within the same. These reinforcements comprise stiffening angles 31 which, with the tie-straps 15 hereinbefore referred to, serve to reinforce the body of the car. Additionally, gussets 33 are connected with the inwardly disposed flanges 34 and with the vertical flanges 35 of the vertical side angles and the angles 31 at 20 convenient intervals along the length of the car whereby a rigid structure is provided. As a whole, it will be seen, the floor extends in nearly a horizontal plane. As already mentioned, the floor is reinforced at its outer 25 sides by the side sill angles 36.

The floor is amply braced and made rigid, transversely, by the straps 21^a, 21^b, 22^b, 23^b, 24^b and the angles 31, which latter are preferably bolted to the straps through the 30 planking, as shown at 32 in Fig. 3, as well as by the end walls, which are connected to the side walls. Longitudinally, likewise, it is effectively braced by the sills 13, 14, and 36. The straps and the transverse members 31 also serve (as well as the ends) for supporting the outer floor sections from the sills 13, 14.

Having thus described my invention what I claim is:—

40 1. In a mine car, a lading receptacle, a floor comprising a plurality of longitudinally extending planks and a plurality of angle members extending between said planks and beyond said receptacle at each end thereof and a metal sheathing enveloping the greater portions of the ends of said planks at each end all of said parts being rigidly connected together.

50 2. In a mine car, a lading receptacle, a floor comprising a plurality of longitudinally extending planks and a plurality of longitudinally extending angles between and lapping said planks and connected thereto with a sheathing of metal enclosing one end 55 of said planks; the planks, angles and sheathing being connected and adapted to cooperate in resisting buffing stresses.

60 3. In a mine car comprising a centrally disposed wooden floor divided into longitudinally extending sections, cross braces connected with said wood floor sections and angles extending longitudinally thereof between certain of said floor sections so as to resist buffing shocks.

65 4. In a mine car, wheels, axles and axle

boxes and side and end walls; a central wood floor extending between the wheels, side floor sections extending outwardly from said central floor portion, metallic stiffening members extending between said central floor and 70 the side sections and resting on said axle boxes and transverse floor supports carried by said stiffening members.

5. In a mine car having side and end walls, a central wood floor portion, side floor portions, metal sills between the central and side floor portions and substantially coextensive with said central floor section, axle boxes supporting said sills and transverse members supporting the side floor from said sills. 75

6. In a mine car having a central wood floor portion, terminating in end bumper sections, side floor portions, a pair of sills lapping said central floor portion between the same and said side floor portions and extending at each side of said bumper sections, axle boxes connected with said sills, and transverse floor supports connecting said sills. 80

7. In a center bumper mine car having side and end walls, a wood floor extending beyond said end walls to form bumpers, angle sills at the sides of said wood floor and the bumpers, axle boxes supporting said sills and cross ties connected therewith and to the axle boxes. 90

8. In a mine car, a wood floor, longitudinal supporting angles lapping the side edges thereof, axle boxes, and axle housings under said floor connecting said angles. 95

9. In a mine car, a wood floor terminating in a bumper portion, angles lapping the side edges of said floor including the bumper portion, and axle housings connecting said angles. 100

10. In a mine car, a body portion comprising angular sills, a wood floor intermediate said sills, axle boxes connected to said sills and axle housings resting on and connecting said axle boxes. 105

11. In a mine car, a central wood floor section, angular sills at each side thereof, axle boxes supporting said sills, a plurality of outer side floor portions extending outward from said sills, and means supporting said outer side floor portions from said sills. 110

12. In a mine car, axle boxes, longitudinal angles resting on said axle boxes, transverse members connecting said angles, a wood floor supported by said angles and transverse members, side floor extensions outward from the outer sides of said angles and means for supporting said side floor extensions. 115

13. In a mine car, a central wood floor and longitudinal metal sills in substantially the same plane, auxiliary side floor portions provided with openings for wheels which wheels are adapted to intersect the plane of said central floor, said floor portions extending between and beyond said wheel openings, hoods over said openings and means sup- 120

125

- ported by said sills and central wood floor for supporting said auxiliary side floor portions.
14. In a mine car, a central wood floor and longitudinal metal sills in substantially the same plane, auxiliary side floor portions provided with wheel openings and transverse members above said central wood floor for supporting said auxiliary side floor portions.
- 10 15. In a mine car, a central wood floor and longitudinal metal sills partly in the same plane, auxiliary side floor portions provided with openings for wheels which are adapted to intersect the plane of said central floor, said floor portions extending between and beyond said wheel openings, hoods over said openings and transversely extending means for supporting said sills and central wood floor.
- 15 16. In a mine car, a central wood floor and longitudinal rolled angle sills in substantially the same plane, auxiliary side floor portions provided with wheel openings and transverse members below said central wood floor for supporting all of said floor portions.
- 20 17. In a mine car, a central wood floor and longitudinally extending angle sills in substantially the same plane, auxiliary side floor portions provided with wheel openings, said side floor portions extending between and beyond said wheel openings, hoods over said openings and means supported by said sills for supporting said auxiliary side floor portions.
- 30 18. In a mine car, a central wood floor and auxiliary side floor portions provided with wheel openings longitudinally extending angular sills below and between boards of the floor, and transverse members connected with said central wood floor for supporting said auxiliary side floor portions.
- 40 19. In a mine car, wheels, axles and axle boxes and side and end walls; a central wood floor extending between the wheels, side floor sections extending outwardly from said central floor portion, metallic stiffening members extending between boards of the floor, and means carried by said axles and axle boxes adapted to support said central wood floor, said side floor sections and said walls.
- 50 20. In a mine car having side and end walls, a central wood floor portion, side floor portions, metal sills between and in the plane of boards of the floor portions and substantially co-extensive with said central floor section, axle boxes and transverse members between the axle boxes supporting said floor portions.
- 55 21. In a center bumper mine car having side and end walls, a wood floor extending beyond said end walls to form bumpers, angles in the plane of said wood floor and the bumpers, axle boxes supporting said floor and cross ties connected with said floor and to the axle boxes.
22. In a mine car, a central wood floor section, angles in the general plane of said wood floor, axle boxes and transverse members connected thereto supporting said wood floor, a plurality of outer side floor portions and means supporting said outer side floor portions from said central wood floor.
- 70 23. In a mine car, axle boxes, longitudinal angles supported by said axle boxes, transverse members connecting said angles, a wood floor supported by said angles and transverse members, side floor extensions at the outer side of said angles and means for supporting said side floor extensions.
- 75 24. In a mine car, a central wood floor and longitudinal metal sills in substantially the same plane, auxiliary side floor portions provided with openings for wheels which wheels are adapted to intersect the plane of said central floor, said floor portions extending between and beyond said wheel openings, hoods over said openings, means for supporting said central floor and means supported by said central wood floor for supporting said auxiliary side floor portions.
- 80 25. In a mine car having side and end walls and end bumpers, wheels, axles, journal boxes; a central wood floor extending between and supported by said wheels, axles and journal boxes; side floor sections extending outwardly from said central floor portion; and metallic stiffening members extending between said central floor and said side floor sections.
- 85 90 26. In a mine car having side and end walls and end bumpers, a central wood floor extending between the car wheels and beyond an end wall, side floor sections extending outwardly from said central floor portion, and metallic stiffening members extending between said central floor and the side sections and beyond said end wall, thereby reinforcing the central floor portion.
- 95 100 105 27. In a mine car having side and end walls, a central wood floor portion longer than the distance between the end walls, a metallic stiffening member secured at each side of and substantially coextensive with said central floor portion, axle boxes and transverse connecting members connected with said stiffening members, and side floor sections extending outwardly from said central floor portion.
- 110 115 120 28. In a mine car having side and end walls, a central wood floor portion, a metallic stiffening member secured at each side of and substantially coextensive with said central floor portion, axle boxes connected with said stiffening members, and side floor sections extending outwardly from said central floor portion.
- In witness whereof I have hereunto set my hand,
- WALTER S. PURDY.
